UNITED STATES PATENT OFFICE.

JOSEPH RUBINO, OF ORANGE, NEW JERSEY, ASSIGNOR TO THOMAS A. EDISON, INCORPORATED, OF WEST ORANGE, NEW JERSEY, A CORPORATION OF NEW JERSEY.

DESIGN FOR A CABINET.

43,896.

Specification for Design.

Patented Apr. 22, 1913.

Application filed January 22, 1913. Serial No. 743,668. Term of patent 14 years.

To all whom it may concern:

Be it known that I, JOSEPH RUBINO, a subject of the King of Italy, residing at Orange, in the county of Essex and State of New Jersey, have invented a new, original, and ornamental Design for Cabinets, of which the following is a specification, reference being had to the accompanying drawing, forming a part thereof.

The figure is a perspective view of a cabinet showing my new design.

I claim:

The ornamental design for a cabinet as shown.

JOSEPH RUBINO.

Witnesses:

FREDERICK BACHMANN,
MARY J. LAIDLAW.
